CIRCUIT BREAKER

Edmund O. Schweitzer, Jr., Northbrook, Ill.

Application September 26, 1936, Serial No. 102,633

5 Claims. (Cl. 200—152)

My invention relates, generally, to circuit breakers and it has particular relation to circuit breakers for use in connection with high voltage power circuits. This application constitutes a continuation, in part, of my copending application, Serial No. 64,800, filed February 20, 1936.

In my copending application I have disclosed means for effecting the final break in an electric circuit between two portions of a non-metallic 10 conducting liquid for the purpose of reducing the possibility of the formation of an arc which is ordinarily formed when an electric circuit carrying current is opened. For this purpose I have provided a pair of separable contact members, 15 one of which is immersed in a suitable non-metallic liquid, such as a dilute solution of sulphuric acid, hydrochloric acid, zinc sulphate, and the like, while the other contact member is mounted for movement into and out of the liquid. 20 Surrounding the lower end of the movable contact member is a cup formed of insulating material that is arranged to always maintain a portion of the liquid in engagement therewith. When the movable contact member carrying the 25 insulating cup at its lower end is removed from the liquid, the circuit between the contact members is broken between two portions of the conducting liquid, rather than between the conducting liquid and one of the contact members. 30 When this type of circuit opening is employed there is little, if any, tendency for an arc to be formed for the reason that the thermionic emission, which is present when a circuit is broken between metallic contact members or between a 35 metallic contact member and a conducting liquid, is absent. Moreover, since the specific heat of the conducting liquid is relatively high as compared to that of a metal, such as copper, the rise in temperature of the non-metallic conducting liquid will be relatively small as compared to the temperature rise of metallic contact members 40 when a circuit is opened thereby.

The object of the present invention, generally stated, is to apply the foregoing principles of operation to a commercial form of circuit breaker which shall be simple and efficient in operation and which may be readily and economically manufactured and installed.

An important object of my invention is to provide for opening a high voltage electric circuit between two portions of a non-metallic conducting liquid.

Another important object of my invention is to provide for opening a high voltage electric circuit between two portions of a non-metallic con-

ducting fluid at a plurality of individual points in the circuit.

A further object of my invention is to provide a circuit breaker having two separate conducting circuits, one through a non-metallic conducting liquid and the other through a metallic shunt member, together with operating means for first opening the circuit through the shunt member and then the remaining circuit between two portions of the conducting liquid.

Still another object of my invention is to provide for opening an electric circuit between two portions of a non-metallic conducting liquid in each of a pair of series connected chambers.

Other objects of my invention will, in part, be obvious and in part appear hereinafter.

My invention, accordingly, is disclosed in the embodiment hereof shown in the accompanying drawing, and it comprises the features of construction, combination of elements, and arrangement of parts which will be exemplified in the construction hereinafter set forth, and the scope of the application of which will be indicated in the appended claims.

For a more complete understanding of the nature and scope of my invention, reference may be had to the following detailed description, taken in connection with the accompanying drawing, in which:

Figure 1 is a view, partly in side elevation and partly in section, showing a concrete embodiment of my invention;

Figure 2 is an enlarged view, in top plan, showing the construction of the insulating cup at the lower end of each of the movable contact members in detail; and

Figure 3 is a sectional view taken along the line 3—3 of Figure 2.

According to the present invention, I have provided for embodying the principles of operation of the circuit breaker disclosed in my copending application, hereinbefore referred to, in one form of a commercial type of circuit breaker which is employed in connection with high voltage power circuits. This particular form of circuit breaker, in its commercial embodiment as now available in the open market, includes a pair of fixed contact members, which are suitably insulated, and which are arranged for connection into an electric circuit. Each of the contact members is provided with an arcing chamber which is partly filled with a suitable non-conducting liquid, such as a halogenated hydrocarbon. A connecting member comprising a pair of contact rods connected by a suitable yoke is pro-

vided and connected to a suitable operating mechanism. The contact rods are arranged to move in the arcing chambers through the insulating liquid and into contact engagement with the 5 fixed contact members. When the connecting member is moved upwardly, the circuit is broken in each arcing chamber when the contact rod therein leaves its individual fixed contact member. The arc which is formed when the circuit is 10 broken when carrying current is extinguished by means of the insulating liquid. If the circuit is carrying a large current, correspondingly severe arcing conditions may arise which require special 15 precautions to be taken in order to avoid damage to the circuit breaker itself and possible damage to surrounding equipment.

By applying the principle of opening a circuit between two portions of a non-metallic conducting liquid to a circuit breaker of this type, I have 20 been able to open circuits carrying very heavy currents with substantially no arcing. I substitute a non-metallic conducting liquid for the insulating liquid in the arcing chambers and provide each of the contact rods or, in this case, electrodes, at its lower end, with a cup formed of insulating material which is arranged to always 25 maintain a portion of the conducting liquid in engagement with the electrode. When the electrodes are moved upwardly to open the circuit, 30 the final break occurs between two portions of the conducting liquid, rather than between two metallic contact members, as was formerly the case.

Referring now particularly to Figure 1 of the drawing, it will be observed that the reference 35 character 10 designates, generally, a commercial form of circuit breaker to which my invention has been applied for the purpose of increasing its rupturing capacity and providing substantially arcless operation. As illustrated, the circuit 40 breaker 10 comprises a housing 11 having insulators 12 and 13 extending through the bottom wall thereof for insulating conductors 14 and 15 therefrom. The conductors 14 and 15 may be connected to an electric circuit in a manner 45 well known to those skilled in the art. The conductors 14 and 15 are provided at their upper ends with terminal members or electrodes 16 and 17 which have liquid pots or chambers 18 and 19 connected thereto and forming extensions thereof in an upward direction. The chambers 18 and 50 19 are composed preferably of a conducting material, such as copper, and they form the arcing chambers of a commercial form of circuit breaker. The interior construction of the chambers 18 and 55 19 may be identical, chamber 18 being illustrated in section by way of example. As shown, the chamber 18 is provided with a lining 24 of insulating material, such as fiber, having an apertured cap 25 at the upper end thereof. A bath 26 60 of a suitable non-metallic conducting liquid is poured into the chamber 18 to the level indicated at 27. As set forth hereinbefore, this liquid may comprise a dilute solution of sulphuric acid, hydrochloric acid, zinc sulphate, or the like. A common salt solution may also be employed.

Each of the chambers 18 and 19 is provided 65 with a movable electrode, 28 and 29, respectively, which are slidably mounted in suitable insulators 30 and 31 that are mounted at the upper ends 70 of the chambers 18 and 19, as illustrated. The electrodes 28 and 29 are mechanically and electrically interconnected by a yoke 32 which is carried by an operating rod 33 that forms a part of an operating mechanism designated generally by the 75 reference character 34. The operating mecha-

nism 34 may be of any suitable type which is arranged to move the operating rod 33 upwardly a sufficient distance to open the circuit in the desired manner. Since any suitable operating mechanism, well known to those skilled in the art, may be employed, a detailed description thereof is not set forth herein.

In order to provide a shunt path between the conductors 14 and 15 so that the liquid 26 will not be required to conduct line currents under normal operating conditions, a shunting member 35 is provided which may be carried by and therefore operated in conjunction with the yoke 32. The shunting member 35 may comprise a plurality of laminations of copper to provide the required conducting characteristics. The ends of the shunting member 35 are arranged to engage contact blocks 36 and 37 that are carried by the chambers 18 and 19. It will be recalled that the chambers 18 and 19 are formed of conducting material and, therefore, when the shunting member 35 is in engagement with the contact blocks 36 and 37 a complete metallic circuit is provided between the conductors 14 and 15.

With a view to providing for the final break in 25 each of the chambers 18 and 19 between two portions of the liquid 26, the lower end of each of the electrodes 28 and 29 is provided with a cup 40, the details of construction of which are illustrated more clearly in Figures 2 and 3 of the 30 drawing. As there shown, the cup 40 is formed of insulating material, such as a phenolic condensation product. The cup 40 is internally threaded to receive a contact plate 41 in threaded engagement therewith. The contact plate 41 is 35 formed of conducting material such as copper and is provided with an internally threaded boss 42 for mounting on the lower threaded end of the electrodes 28 and 29.

It will be understood that the cup 40 is filled 40 with the conducting liquid 26 which will then be in contact engagement with the contact plate 41. With a view to insuring that the circuit will be broken between two portions of the liquid 26 a cover 43, having apertures 44 near the periphery 45 thereof, is threaded into the upper end of the cup 40, as illustrated. Since the cover 43 is formed of a suitable insulating material and further, since a sleeve 45 of insulation is provided around the rod 28, the only path through which the current can 50 flow from the contact plate 41 is through the apertures 44. There is then no likelihood of an arc being formed because of the breaking of the circuit between the metallic contact plate 42 and a portion of the conducting liquid 26 or between the 55 electrodes 28 and 29 and the conducting liquid 26.

In operation, the normally closed position of the circuit breaker 10 and the various parts thereof is shown by the full lines in Figure 1 of the drawing. When it is desired to open the circuit, the operating rod 33 is moved upwardly by the operating mechanism 34 in the conventional manner. The shunt member 35 is first moved out of engagement with the contact blocks 36 and 37, thereby transferring the entire flow of current to 65 the conducting liquid 26 in each of the chambers 18 and 19. The continued upward movement of the operating rod 33 lifts the cup 40 carried by each electrode 28 and 29 out of the conducting liquid 26. Because of the provision of the cups 70 40, it will be understood that the circuit is finally broken between two portions of the conducting liquid 26 in each of the chambers 18 and 19, thereby providing two breaks in series between the conductors 14 and 15. The yoke 32 and oper- 75

ating elements carried thereby is moved to the alternate position shown by the broken lines. In order to close the circuit, the foregoing described sequence of operation is reversed and the operating rod 33 is moved downwardly, as will be readily understood.

Since certain changes may be made in the above construction and different embodiments of the invention may be made without departing 10 from the scope thereof, it is intended that all matter contained in the above description or shown in the accompanying drawing shall be interpreted as illustrative and not in a limiting sense.

15 I claim as my invention:

1. An electric switch comprising, in combination, two fixed electrodes, a separate enclosure for each of said electrodes, two mechanically and electrically connected movable electrodes adapted 20 to be moved toward and away from said fixed electrodes in said enclosures, a non-metallic conducting liquid in each of said enclosures for completing a circuit between said electrodes in said enclosures, and means for breaking said circuit in 25 each enclosure between two portions of said liquid therein to provide an air gap between the electrodes in each enclosure.

2. An electric switch comprising, in combination, two fixed electrodes, a separate enclosure 30 for each of said electrodes, two mechanically and electrically connected movable electrodes adapted to be moved toward and away from said fixed electrodes in said enclosures, a non-metallic conducting liquid in each of said enclosures for completing a circuit between said electrodes in said 35 enclosures, shunt circuit means also completing a circuit between said fixed electrodes through said liquid, and means for sequentially opening said circuits including means for first opening the 40 circuit completed by said shunt circuit means and means for opening the remaining circuit between two portions of said liquid in each enclosure to provide an air gap between the electrodes in each enclosure.

45 3. An electrical circuit breaking device comprising, in combination, a pair of fixed electrodes

mounted in insulated spaced relation, a chamber composed of conducting material individual to each electrode, a body of non-metallic conducting liquid in each chamber, an electrode mounted for relative movement with respect to said liquid 5 in each chamber, means interconnecting said movable electrodes to complete a circuit between said fixed electrodes through said liquid, shunt means engaging said chambers for also completing a circuit between said fixed electrodes, and 10 means for sequentially opening said circuits including means for first opening the circuit completed by said shunt circuit means, and means carried by each movable electrode for opening the remaining circuit between two portions of 15 said liquid in each chamber to provide an air gap between the electrodes in each chamber.

4. An electrical circuit breaking device comprising, in combination, a pair of fixed electrodes mounted in insulated spaced relation, a chamber 20 individual to each electrode, a body of non-metallic conducting liquid in each chamber, an electrode mounted for relative movement with respect to said liquid in each chamber, means interconnecting said movable electrodes to complete a circuit between said fixed electrodes through said liquid, and a cup composed of 25 insulating material mounted at the lower end of each movable electrode for maintaining a portion of said conducting liquid in engagement 30 therewith whereby said circuit is opened between two portions of said liquid in each chamber when the movable electrodes are moved to the circuit opening position to provide an air gap between the electrodes in each chamber.

5. The combination, with a contact member of an electrical circuit breaking device movable relative to a bath of non-metallic liquid, of a contact plate fastened to the lower end of said contact member, a cup formed of insulating material 40 and carried by said plate and disposed to maintain the liquid in contact therewith, and an apertured cover formed of insulating material covering said cup.

EDMUND O. SCHWEITZER, JR.
